UNITED STATES PATENT OFFICE

2,524,552

HYDRAULIC ACTUATOR FOR TURBINE
STOP VALVES

Lawrence B. Wales, Marblehead, Mass., and
Frank C. Linn, Schenectady, N. Y., assignors to
General Electric Company, a corporation of
New York

Application November 16, 1946, Serial No. 710,366

6 Claims. (Cl. 121—38)

1

This invention relates to valve actuating mechanisms, more particularly to a hydraulic motor actuator for quick-acting stop or shut-off valves such as those for controlling the flow of a fluid operating medium to a prime mover, for instance a steam turbine.

In steam turbine powerplants it is usual to have a stop valve arranged to quickly shut off the flow of operating medium to the turbine, the valve being controlled by the emergency overspeed governor of the turbine. Such valves are ordinarily arranged to have a wide open and a fully closed position, and are positioned by a suitable motor, preferably a positive displacement hydraulic motor.

Heretofore, it has been customary in hydraulic motors for valves of this type to provide two liquid supply conduits and one discharge conduit. One supply conduit furnished the fluid necessary to actuate a "relay valve," and a separate supply conduit furnished the fluid for actuating the hydraulic motor to position the valve. By contrast, a valve actuating mechanism in accordance with this invention requires only one supply conduit which furnishes liquid to both a relay valve and the hydraulic motor in series, thus eliminating one fluid supply conduit.

An object of the invention is to provide an improved actuating mechanism for a quick-acting, shut-off valve.

Another object is to provide an improved hydraulic motor having a novel relay valve arrangement for controlling the motor.

A further object is to provide an improved hydraulic actuating mechanism of the type described having a simplified piping arrangement.

Other objects and advantages will be apparent from the following description taken in connection with the accompanying drawings, in which Fig. 1 is a schematic drawing of a prime mover powerplant having a quick-acting shut-off valve embodying the invention; and Fig. 2 is a sectional view of the valve and motor assembly 5, 6, 7 of Fig. 1.

Referring now to Fig. 1, it will be seen that a prime mover such as a steam turbine 3 is supplied with fluid operating medium through a conduit 4 containing a shut-off valve 5 actuated by a hydraulic motor 6 under the control of a relay valve 7. A liquid supply pump 10 draws liquid from a reservoir 11 through a conduit 12 containing check valve 81 and is driven by suitable gearing 9 from the shaft 8 of the prime mover.

It will be understood by those familiar with this art that pump means independent of the prime

2

mover is necessary for supplying hydraulic pressure when the prime mover is at rest. This may conveniently be in the form of a liquid supply pump 10a driven by electric motor 9a and in parallel with the prime mover driven pump 10, as shown in Fig. 1. Pump 10a is arranged in conduit 12a, containing check valve 81a.

A valve 13 is provided in the pump discharge conduit 80 and comprises a housing 14 having an inlet port 15, an outlet port 16, and a drain conduit 17. The valve stem 18 is biased downwardly by coil spring 19 and carries a pair of axially spaced discs 20 and 21 arranged to cooperate with seats 20a and 21a, respectively. During normal operation of the powerplant, stem 18 is engaged by a spring biased latch 22, thus seating disc 21 to shut off communication with drain conduit 17 and unseating disc 20 so that inlet port 15 is in communication with outlet port 16. Latch 22 is arranged to be tripped by an emergency governor 23 which is carried on shaft 8 of the prime mover 3.

Liquid under pressure from supply pump 10 passes through control valve 13 to the relay valve 25 through conduit 80. Spent operating liquid is discharged from the relay valve 7 to reservoir 11 through a conduit 79. Preferably the low pressure drain conduit 79 is arranged to enclose the high pressure supply conduit 80, in a manner 30 and for purposes well known to those skilled in this art.

The sectional view of Fig. 2 shows details of the relay valve 7 and valve 5, in the "closed" position. Shut-off valve 5 comprises a housing 24 provided with a port 25 opening into an inlet chamber 26. A ring member 27 forms a valve seat and is secured in housing 24 by suitable means, as by welding at 27a. A discharge chamber 28 communicates with an outlet port 29. For improving the aerodynamic performance, a shield in the form of a hollow cylinder 30 is secured to the removable head 31. This shield arrangement is not a part of the present invention but is disclosed more completely in the copending application of G. B. Warren and E. E. Parker, Serial No. 592,322, filed May 7, 1945, and assigned to the same assignee as the present application and now Patent No. 2,483,163, issued September 27, 1949. The valve disc assembly 32 is arranged to seat against ring member 27 and is carried on the free end of a valve stem 33 which is slidably disposed in a support and sealing bushing assembly 34. The valve stem 33 is adapted for connection by a coupling sleeve 35 to a piston rod 36 of motor 6.

The hydraulic motor 6 comprises a housing 37 to which is secured a cylinder head 38 by suitable threaded fastenings 39. Formed integral with cylinder head 38 is a bracket 40 secured to valve housing 24 by threaded fastenings 41 so as to support the motor 6 rigidly from the main valve housing. Slidably arranged in housing 37 is a piston 42 biased to its downward position by a coil spring 43. Spring 43 is seated at the top in an annular recess 44 formed in the cylinder head 38 and at the bottom in a recess 45 formed in the piston 42. Suitable piston rings 46 are provided to reduce leakage around piston 42 to a minimum. Any leakage past the piston which does occur will be drained through a port 47 in the housing 37, thence through drain conduit 48 into the discharge chamber 49 of relay valve 1. Piston rod 36 is slidably arranged in a packing gland 50 and is connected to piston 42 by means of a head 51 which engages the inner surface of a recess in the under side of piston 42. A threaded plug 52 is screwed into the recess to retain head 51.

The relay valve 1 has an outer housing 53 with an end plate 54 secured to a flange 55 by suitable threaded fastenings 56. A threaded drain plug 57 may be provided in plate 54. Formed integral with motor housing 37 is the relay valve cylinder 58 having an inlet port 59 into which liquid supply conduit 80 is threaded. Secured to the cylinder 58 by threaded fastenings 61 is a head 62 carrying a piston stop member in the form of a hollow cylinder 63 with one or more ports 64 arranged to permit liquid to enter and fill the bore 63a of the stop cylinder. A plunger 65 is slidably arranged in cylinder 58 and is biased downwardly by a coil spring 66 so as to rest on the end of stop member 63, as will be apparent from the drawing. Plunger 65 fits loosely around the stop 63. A restricted orifice 67, the purpose of which will appear hereinafter, is provided in the upper end of plunger 65. Formed in housing 37 above the plunger 65 is a port 68 which admits operating liquid from relay valve 1 to motor 6. A cylindrical liner 69 may be secured in cylinder 58, by pressing, shrinking or other method, to provide a smooth sliding surface for the plunger 65. A piston ring 70 is arranged to keep fluid leakage around the plunger 65 to a minimum. One or several ports 71 are provided in cylinder 58 so that any leakage past piston 65 can return to the discharge chamber 49. Ports 71 have the additional important function of providing a large area passage for draining fluid from beneath the motor piston 42, thus permitting the shut-off valve disc 32 to descend rapidly, under the influence of biasing spring 43 when the supply of operating liquid to the motor 6 is discontinued.

Manual control means may be provided in the form of lever 72, arranged so that the valve actuating mechanism can be tested without disturbing the emergency governor 23 or control valve 13 of Fig. 1. Lever 72 is pivoted to the coupling sleeve 35 and is fulcrumed on a rod 73 by means of a yoke 78. Rod 73 is slidably arranged in a bore in housing 37 and is of sufficient length so as to extend across conduit 74 and into a port 75 which is arranged to communicate between conduit 74 and chamber 49. A bushing 76 threaded into housing 37 at the upper end of rod 73 serves to minimize leakage around rod 73 and also provides a stop when raising or lowering lever 72. Upward movement of rod 73 is limited by engagement of shoulder 77 with bushing 76,

while downward movement is limited by engagement of yoke 78 with the top surface of the bushing.

The operation of our improved hydraulic actuator is as follows:

A flanged conduit 79a communicates with the drain chamber 49 of relay valve 1, and is connected to the drain conduit 79. Liquid from supply conduit 80 enters the relay valve inlet chamber 60, from whence it flows through ports 64 filling the interior of stop member 63 and then passes through orifice 67. Because of the pressure differential thus created across the restricted orifice 67, a net upward force will be exerted on the plunger 65. The liquid also fills inlet chamber 60 exerting a pressure on the bottom end of plunger 65. As a result of these hydraulic forces on it, plunger 65 moves upwardly against the bias of spring 66, causing the beveled upper end of the plunger to seat against the valve seat formed by the beveled edge of port 68. In so doing, the discharge ports 71 are sealed off from the liquid flow and all fluid passing through orifice 67 will pass through port 68 and build up a pressure on the underside of the motor piston 42, causing it to move upwardly against the action of spring 43, thereby unseating the valve disc assembly 32. Motive fluid is thus permitted to flow through conduit 4 to the prime mover 3. During normal operation, liquid pressure is maintained on motor piston 42, so that valve disc 32 is held open. The plunger 65 is held in raised position with the top end portion thereof sealing off port 68 as long as liquid pressure is applied to the lower surface of the piston formed by the lower end portion of the plunger, by reason of the fact that the effective area of the lower end surface of the plunger is greater than that of the upper end surface exposed to the fluid pressure within port 68, as will be apparent in Fig. 2.

It may be noted that since the flow of motive liquid to motor 6 is limited by orifice 67, the rate of rise of valve disc 32 from the fully closed to the wide open position may be preselected by suitably proportioning the orifice.

Assuming now that an overspeed condition occurs in the prime mover 3, the emergency governor 23 will trip latch 22 permitting spring 19 to move spindle 18 downwardly, causing valve disc 20 to seat and disc 21 to unseat. Thus the liquid supply to conduit 80 is shut off and communication between conduit 80 and drain conduit 17 is established. This releases the fluid pressure from the underside of relay valve plunger 65. The action of spring 66 combined with the pressure of the liquid communicated to the upper surface of plunger 65 through port 68, causes the plunger 65 to move downwardly until it rests on the end of the stop 63. In so doing, the liquid pressure is released from beneath the hydraulic motor piston 42. The liquid will pass through the port 68, around the outside of plunger 65, and through the drain ports 71 into the chamber 49, whence it leaves through outlet conduit 79a and returns to the reservoir 11 through conduit 79. Because of the generous proportions of the ports 68, 71, 79a, and the related passages, the liquid is quickly drained from the motor 6 and the valve disc 32 is rapidly lowered to seat on member 27, thus shutting off the flow of operating medium to the prime mover.

For testing purposes, the valve may be tripped manually by raising the lever 72. The liquid below piston 42 will then pass through conduit

74, and port 75 to the discharge chamber 49, thence to reservoir 11 through conduit 79.

In case of either automatic or manual tripping of the valve, when fluid pressure is released from the motor 6, the action of spring 43 will cause piston 42 to move rapidly downwardly, thus quickly seating the valve disc 32 and shutting off the supply of operating medium to the prime mover.

By arranging the relay valve in series with the hydraulic motor, as described, only a single hydraulic supply conduit is required.

Thus, the invention provides an improved hydraulic valve actuating mechanism, arranged to be simple and reliable mechanically, and requiring a minimum amount of piping.

While a particular embodiment of the invention has been illustrated and described, it will be obvious to those familiar with the art that various changes and modifications may be made without departing from the invention; and it is intended to cover in the appended claims all such changes and modifications as come within the true spirit and scope of the invention.

What we claim as new and desire to secure by Letters Patent of the United States, is:

1. In a hydraulic motor, the combination of a motor cylinder with a piston member slidably disposed therein, a relay valve cylinder having one end closed and the other end secured to the motor cylinder and having a plunger member slidably disposed therein, conduit means for supplying operating liquid to the closed end of the relay cylinder, walls defining a first port communicating between the relay cylinder and the motor cylinder, spring means biasing said piston to an extreme position nearest the first port, walls defining a second drain port through the relay cylinder wall adjacent the first port, said plunger having a first end portion adapted to close the first port and block communication between the first and second ports when in one extreme position, the other end portion of the plunger forming a piston of greater effective area than that of said first end portion, said plunger having a restricted passage extending entirely therethrough and adapted to communicate liquid from the supply conduit to the first port when in said extreme position, and spring means biasing the plunger toward the closed end of the relay cylinder so as to uncover the first port and provide direct communication with the second port, whereby liquid is drained from the motor cylinder through the first and second ports when the supply thereof is discontinued, the pressure drop across said restricted passage serving to move the plunger to said extreme position when pressure liquid is supplied to the closed end of the relay cylinder.

2. In a hydraulic motor, the combination of a motor cylinder having a piston slidably disposed therein, means biasing the piston to one extreme position in its range of movement, said cylinder having a first port adapted to supply liquid to the cylinder for moving the piston toward the other extreme of its range of movement, and a relay valve cylinder connected to the motor cylinder with one end in communication with the first port, said relay cylinder having a drain port opening through the wall thereof adjacent the first port, a plunger slidably disposed in the relay cylinder and having a first end portion adapted to close the first port to interrupt communication between the first port and the drain port when in a first extreme posi-

tion, said first plunger and plunger portion having a restricted passage extending axially through the plunger and adapted to communicate between the first port and the relay valve cylinder when in said first extreme position, the other end portion of the plunger forming a second piston having an effective area larger than that of the first plunger end portion, spring means biasing the plunger away from said first position to the opposite extreme position in which the first port is in free communication with the drain port, and means for supplying liquid under pressure to the relay cylinder only at the side of the plunger remote from the first port whereby the pressure drop in the liquid passing through said restricted passage to the motor cylinder causes the plunger to move to said first extreme position and the static pressure of the liquid acting on said second piston serves to hold the plunger in said first extreme position as long as the liquid supply pressure is maintained.

3. In a hydraulic motor, the combination of a motor cylinder with a piston member disposed therein, means biasing the piston toward one extreme position in its range of movement, said cylinder having a wall portion defining a combined liquid supply and drain port for admitting liquid to cause the piston to move toward the other extreme position in its range of movement, a relay valve for controlling the flow of liquid through said first port and including a relay cylinder having a closed end and an open end communicating with said port and a second drain port opening through the wall of the relay cylinder adjacent the first port and communicating with the exterior of the relay cylinder, and a plunger member slidably arranged in the relay cylinder and having a first end portion adapted to cover the first port to interrupt communication thereof with the second port when in a first extreme position, said plunger having a restricted axially extending passage opening through both ends thereof, the second end portion of the plunger having a second piston with an effective area larger than that of the first plunger end portion, spring means biasing the plunger toward the closed end of the relay cylinder to establish communication between said first and second ports, and means for supplying liquid under pressure to the closed end of the relay cylinder only whereby the pressure drop across the restricted passage causes the plunger to move to said first extreme position when liquid flows through said passage and the first port to the motor cylinder and the supply pressure acting on said second piston holds the plunger in said first position as long as the pressure is maintained.

4. In a hydraulic motor, the combination of a housing defining a chamber with an inlet port, a first movable member disposed in the chamber and adapted to be actuated to an extreme position by pressure fluid admitted to the chamber through said port, means biasing the movable member to an opposite extreme position, conduit means for supplying operating fluid to the inlet port, and relay valve means interposed between said conduit and port, the relay valve including a casing having a closed end communicating with the supply conduit at the other end in communication with the inlet port and a drain port adjacent the inlet port, and a second movable member disposed in the casing and having

a first end portion adapted to cover the inlet port to interrupt communication between the inlet port and the drain port when in a first extreme position, the second movable member having a second end portion defining a second piston of an effective area larger than said first end portion, spring means biasing the second movable member toward the closed end of the casing, the second movable member having a restricted passage extending axially through both ends thereof and adapted to establish communication between the supply conduit and the inlet port when in said first extreme position, whereby said second member is caused to move to its first extreme position under the influence of the pressure differential created across the restricted passage when liquid is supplied therethrough to the motor chamber and the supply pressure acting on said second piston holds the second member in said first position as long as the supply pressure is maintained.

5. In a hydraulic motor, the combination of a motor cylinder having an operating liquid port in one end thereof and a slidably disposed piston therein, means biasing the piston toward said port, and a relay valve assembly for controlling the supply of operating liquid to the port including a relay valve cylinder secured to the motor cylinder and having a closed end remote from the motor cylinder and an open end in communication with said port, the relay cylinder having a drain port through the wall thereof adjacent said first port, a plunger member slidably disposed in the relay cylinder and having a first end portion adapted to close the first port to interrupt communication between the first port and the drain port when in a first extreme position, the plunger having a second end portion with a second piston of an effective area larger than that of said first end portion, spring means biasing the plunger away from said first position toward the closed end of the relay cylinder, said plunger defining a restricted passage adapted to communicate between the first port and the chamber defined by said second piston and the closed end of the relay cylinder, liquid supply conduit means connected to the last-mentioned chamber, a casing secured to the motor cylinder surrounding the relay cylinder and spaced therefrom to define a drain chamber communicating with said drain port, and drain conduit means communicating with said drain chamber.

6. In a hydraulic motor, the combination of a motor cylinder having an operating liquid port in one end thereof and a slidably disposed piston therein, means biasing the piston toward said port, and a relay valve assembly for controlling the supply of operating liquid to the port including a relay valve cylinder secured to the motor cylinder and having a closed end remote from the motor cylinder and an open end in communication with the port, said relay cylinder having a drain port through the wall thereof adjacent said first port, a plunger member slidably disposed in the relay cylinder and having a first end portion adapted to interrupt communication between the first port and the drain port when in a first extreme position, spring means biasing the plunger away from said first position toward the closed end of the relay cylinder, the other end portion of the plunger forming a second piston of an effective area larger than that of said first plunger end portion, said plunger defining a restricted passage adapted to communicate between the first port and the chamber defined by said second piston and the closed end of the relay cylinder, liquid supply conduit means connected to the last-mentioned chamber, a casing secured to the motor cylinder surrounding the relay cylinder and spaced therefrom to define a drain chamber communicating with said drain port, drain conduit means communicating with said drain chamber, walls defining a passage in parallel with said first port and adapted to bypass liquid from the motor cylinder to said drain chamber, valve means in said bypass, and means for actuating said bypass valve to reduce the liquid pressure in the motor cylinder whereby the piston is caused to move towards said first port.
